PUMP

Watt B. Bair, 11255 Camarillo St.,
North Hollywood, Calif. 91602

Filed Feb. 9, 1970, Ser. No. 21,341

Term of patent 14 years

Int. Cl. D23—01

U.S. Cl. D23—14

FIG. 1 is an elevational view of one end of a pump with the handle and connected parts in normal position showing my new design;

FIG. 2 is an elevational view of one side thereof;

FIG. 3 is an elevational view of the other end thereof;

FIG. 4 is an elevational view of the other side thereof;

FIG. 5 is a view similar to FIG. 1 but showing the pump handle and connected parts in a different position; and

FIG. 6 is a plan view of the pump with the handle and connected parts in normal position.

I claim:

The ornamental design for a pump, substantially as shown.
